[57] CLAIM

The ornamental design for a choker line coupler, as
shown and described.

DESCRIPTION

FIGS. 1 and 2 are front and rear perspective views,
respectively, of a choker line coupler in line securing
condition, showing my new design.

FIGS. 3 and 4 are front and rear perspective views,
respectively, of the choker line coupler of FIGS. 1 and
2, in line releasing condition.

FIGS. 5 and 6 are front and rear perspective views,
respectively, similar to FIGS. 1 and 2, of a second em-
bodiment of the choker line coupler in line securing
condition.

FIGS. 7 and 8 are front and rear perspective views,
respectively, of the choker line coupler of FIGS. 5 and
6, in line releasing condition.
